INVENTOR

James D. Douglas
Gen. Off. Baldwin

ATTORNEY

UNITED STATES PATENT OFFICE.

JAMES D. DOUGLAS, OF DETROIT, MICHIGAN.

PORTFOLIO.

Application filed September 21, 1925. Serial No. 57,538.

To all whom it may concern:

Be it known that I, JAMES D. DOUGLAS, a citizen of the United States, residing at Detroit, in the county of Wayne and State of Michigan, have invented a new and useful Portfolio, of which the following is a specification.

This invention aims to provide a portfolio which can also be used as a stand. Its 10 two covers are adapted to open outwards so that they may form two sides of a triangle with the binding, or loose leaf binder, disposed outwardly at the apex, and an element 15 flexibly attached usually at the apex, so that it may be set in an upwardly inclined position. In this manner I provide a portfolio which may be employed as a triangular stand, and, in addition, the element above referred to acts as a support against which 20 upturned leaves may rest so that they are visible from the same side of the portfolio as the downturned leaves which rest against one of the cover members.

Another object of the invention is to provide a portfolio having an extension on one 25 of its cover members which will form the third side of the triangle, or fold inwards over the leaves when the portfolio is closed; the element and its support are also so constructed that they will lie substantially flat 30 against one of the cover members when the portfolio is in closed position.

Having thus briefly outlined the major 35 purposes of the invention I will now proceed to describe an embodiment thereof with the aid of the accompanying drawings in which the various views are drawn to different scales.

Figure 1 illustrates the portfolio with one 40 of the cover members partly open.

Figure 2 shows the portfolio with one cover member more fully open.

Figure 3 is a view of the portfolio in use 45 as a stand, and

Figure 4 shows a modified form of support for the element.

In the drawings, 1 designates the front 50 cover and 2 the back cover, both of which parts are made of strong rigid material. 55 The flexible portion 3 which connects the inner ends of the cover members, has a loose leaf binder 4 attached to it, and the element 5 is also flexibly secured to the portion 3 in proximity to one side of the loose leaf binder. 60 55 Integral with the outer end of the back cover is a flexible portion 6 of sufficient

length to fold over the outer edges of the leaves 7. At the outer end of the flexible portion 6 is an extension piece 8 which is in turn secured to the outer strip 9 by the 65 joint 10.

The inner surface of the front cover is provided with fasteners 11 which are adapted to cooperate either with the fasteners 12 65 on the outer surface of the extension piece 8, or with the fasteners 13 on the outer strip 9.

On the inner surface of the back cover brackets 14 are provided for the supporting member 15 which is pivotally mounted 70 therein, and is adapted either to engage clips 16 and 17 on the back of the element 5 so that the latter may be held in an upwardly inclined position, or to lie substantially flat against the inner surface of the 75 back cover. In Figure 3 a spring clip 17 is shown in addition to the ordinary type of clips 16 shown at the sides; for large portfolios I find it preferable to utilize both forms of clips and to support the element 5 across substantially the whole of its width. 80

In Figure 4 a modified form of construction is shown; a tab 14^a is secured to the inner surface of the back cover and has a flexibly connected extension 15^a which may either be folded back against the inner surface of the cover as shown at 15^b, or brought into engagement with a locking member 17^a secured to the reverse side of the element 5. This form of construction I sometimes employ for small portfolios in which the weight 85 of the leaves is not sufficient to tend to bend the unsupported sides of the element. 90

When the portfolio is in closed position the flexible portion 6 is folded round the outer edges of the leaves 7 and the extension piece 8 and strip 9 lie flat between the inside of the top cover and the leaves. The element 5 is folded back against the inside of the back cover, and the supporting member 15 (or extension 15^a) is folded back towards the outer end of the inner cover and under the element. The portfolio is then held in closed position by engaging the fasteners 11 with the fasteners 12. 100

When it is desired to form the portfolio into a triangular stand, the covers 1 and 2 are opened until their outer surfaces are towards one another, and the distance between their outer edges such that when the extension piece 8 is bent back to form the base 110 of the triangle the fasteners 11 will coact

with the fasteners 13 on the outer strip 9, which has previously been turned upwards about the joint 10. The element 5 is then raised and held in position by the supporting member 15 which engages the clips 16 and 17. Or, in the design shown in Figure 4, the extension 15^a of the tab 14^a is brought into engagement with the locking member 17^a.

- 10 In this manner a stand is provided with the use of which two leaves, one upturned and the other downturned, are visible from one and the same side of the portfolio, whereas without the use of the element 5 15 this would not be the case; and again the arrangement is such that both sides of each leaf may be displayed in turn.

In the foregoing mention has been made of a loose leaf binder though obviously 20 bound leaves may also be arranged in the portfolio. And while the preferred form of construction of the invention has been described and shown, it is understood that any 25 modifications may be made therein that fall within the scope of the appended claims.

What I claim as my invention and desire 30 to secure by Letters Patent is:—

1. A portfolio comprising two cover members connected at their inner ends and adapted 35 to open so that their outer surfaces are towards one another thereby forming two sides of a triangle, an element flexibly mounted in proximity to the inner end of one of the cover members and adapted to 40 assume an upwardly inclined position, means for holding said element in said upwardly inclined position, and means for holding the outer ends of the cover members in spaced relation to one another.
- 40 2. A portfolio comprising two cover members connected at their inner ends and adapted to open so that their outer surfaces are towards one another thereby forming two sides of a triangle, an element flexibly se-

cured to the connecting portion between said 45 cover members, and an extension piece integral with one of said cover members adapted to form the base of the triangle, in combination with means adapted to support 50 said element in an upwardly inclined position.

3. A portfolio as described in claim 2, wherein leaves are so mounted on the connecting portion that upturned leaves may 55 rest against the element and downturned leaves against one of the cover members.

4. A portfolio as described in claim 2, wherein the supporting means for the element extends transversely across the full 60 width of the latter, and wherein means are provided for the element to positively engage the supporting means.

5. In a portfolio, the combination of two 65 cover members, a connecting portion between the inner ends of said cover members, a loose leaf binder on said connecting portion, an element flexibly secured to said connecting portion, and a supporting member for said 70 element pivotally mounted on one of said cover members, said element and said supporting member being adapted to lie substantially flat one on the other against the inner surface of the cover member to which said supporting member is secured when the portfolio is in closed position.

6. A portfolio comprising two cover members connected at their inner ends and adapted to open so that their outer surfaces are towards one another thereby forming two 80 sides of a triangle, an element flexibly mounted in proximity to the inner end of one of the cover members, an extension piece integral with one of the cover members adapted to form the base of the triangle, and a pivotally mounted support on one of the 85 cover members adapted to hold said element in upwardly inclined position.

JAMES D. DOUGLAS.
